UNITED STATES PATENT OFFICE.

JOHN K. GREEN, OF NEW YORK, N. Y., ASSIGNOR TO ELLA D. GREEN, OF NEW YORK, N. Y.

ANCHOR-BOLT.

1,283,156.

Specification of Letters Patent. Patented Oct. 29, 1918.

Application filed November 30, 1915. Serial No. 64,277.

To all whom it may concern:

Be it known that I, JOHN K. GREEN, a citizen of the United States, and a resident of the borough of Manhattan, county, city, and 5 State of New York, have invented certain new and useful Improvements in Anchor-Bolts, set forth in the following specification.

This invention relates to a new anchor 10 bolt for use with safety devices for window cleaners and to a new method of applying anchor bolts for such purposes. The object of the invention is to cheapen and facilitate the manner in which an absolutely secure 15 anchorage for safety window cleaners' devices may be applied to windows during the construction of a building. A further object of the invention is to provide an improved anchor bolt for use in the furtherance of the 20 new method of providing anchorages.

Heretofore it has been customary to install anchor bolts in one of three general ways. One way was to embed a webbed anchor bolt between the partings of the brick 25 or stone work surrounding a window opening during the laying of the brick or stone work. A second way was to drill a hole in the brick work or stone work and secure therein an expansive bolt; a third way was 30 to screw a lag bolt into the woodwork of the window frame. The first way was very expensive, although a satisfactory permanent anchor resulted. The second way was likewise expensive and had the additional disadvantage of relying upon an expansion bolt 35 which often worked loose. The third way has often proven unsatisfactory because of the splitting of the wood.

The present invention marks a radical advance step both in results and method of achievement. An anchor bolt is provided 40 with a flat webbed portion, which has a suitably headed bolt shank formed at its outer end projecting out at a suitable angle so 45 that the same will be exposed in the exact direction best adapted for receiving the strain of safety apparatus when a window is completely framed into a building. This special anchor bolt may with great facility 50 be attached at the proper elevation, one on each side of a window frame, after the completion of the window frame in a shop, but before the same is built into the wall of a building. Thus, when the window frame is 55 in the shop, attaching means such as screws may be used to attach the anchors at locali-

ties where substantially the entire framing of the window frame is engaged by the attaching screws. The particular location of the anchor is also such that the brick or stone 60 work about the window frame will be built up to inclose and embrace the anchor, concealing it to give a good finish and at the same time increasing the strength of its anchorage. This building up of the stone or 65 brick work may be accomplished without the need of paying any particular attention to the anchors as is the case when the same must be applied between the partings of the masonry.

The manner in which the object of the invention is accomplished will be understood from the illustrative embodiments of the invention covered in the accompanying claims, described below and illustrated in the accompanying drawings, which form a part hereof, in which like characters designate corresponding parts, and in which

Figure 1 is a perspective view of the preferred form of the anchor bolt;

Fig. 2 is a horizontal section through one side of a window frame illustrating the anchor bolt in position for use, a section of Fig. 2 being taken along line 2-2 of Fig. 3;

Fig. 3 is a vertical elevation of the assembled structure shown in Fig. 2, parts being broken away along the line 3-3 of Fig. 2;

Fig. 4 is a detail perspective illustrating the manner in which a staff bead may be cut 90 away to accommodate the anchor bolt;

Fig. 5 is a vertical elevation corresponding to Fig. 3 illustrating a modification;

Fig. 6 is a view similar to Fig. 5 illustrating a second modification;

Fig. 7 is a view similar to Fig. 5 illustrating a third modification;

Fig. 8 is a view similar to Fig. 5 illustrating a fourth modification; and

Fig. 9 is a view similar to Fig. 5 illustrating a fifth modification.

In Fig. 1 there is illustrated a flat elongated webbed portion A which is provided with two lateral projections 1 and 2 near the outer end 3 and with a toe 4 at the opposite end 5 occupying a position at right angles to the plane of the webbed portion A. The bolt shank B provided with a bolt head 6 of any desired configuration is preferably cast or forged integral with the webbed portion A and is merged into the same so as to extend outwardly therefrom at an obtuse

angle as shown best in Fig. 2, but should be reinforced at its base in a suitable manner as by buttresses 7, 8 and 9 and webs 10 and 11. Screw holes 12 and 13 are provided in 5 the projections 1 and 2 and also a screw hole 14 in the toe 4. This entire anchorage structure may be termed the anchor bolt, is designated C and may preferably be made of bronze. The projections 1 and 2 and their 10 screw holes 12 and 13 are located so that screws 15 and 16 driven therethrough will pass through the frame-piece 17, through into the stile 18 so that a strong firm anchorage results. The extent of the web portion 15 A is preferably such that the toe 4 grips about the inner edge of the frame-piece 17 and may be secured thereto by suitable means such as the screws shown in dotted lines. The window frame D is fitted with a 20 suitable number of the anchors C suitably positioned. This is done at the factory. When a window frame D is applied to a building and built in by the laying of the masonry E the anchor C is likewise built 25 into the masonry without purposeful effort. In fact an anchor C cannot be removed without practically demolishing the entire window frame and building wall.

When an anchor of the invention has been 30 applied in the manner described and the masonry E has been built up, it is customary to apply to the window frame a staff bead 30. Advantage may be taken of this staff bead to conceal all except the desired amount of 35 shank B and the bolt head 6. All that is necessary is for a carpenter to cut away a suitable socket 31 in the bead 30 to accommodate the parts of the anchor C to be covered as shown in Figs. 2 and 4.

40 To make possible the advantages of this invention, it is contemplated that it is not necessary that the anchor C comprise the exact configuration shown in Figs. 1, 2 and 3. For example in Fig. 5 a modification C' is 45 shown in which the lateral projections 1 and 2 merge into the elongated part of the web portion A along curved lines 20 and 21 which may give added strength to the structure. Another modification is the termination 50 of the elongated web portion at the locality 22 and the provision of a suitable attaching means, such as the screw 23 adapted to pass through the frame-piece 17 into the rear frame-piece 24 of the window frame D.

55 In Fig. 6 in the modification C² the elongated web portion A comprises two legs 25 and 26 making a triangular shaped structure with the front web 27. In this structure the toe 4 is present, although it is contemplated 60 that this triangular construction may

be adapted in the manner shown in Fig. 5 with the elimination of the toe 4.

In Fig. 7 in the modification C³ an L-shaped web portion A is illustrated, the lower lateral projection 1 being omitted. 65

In Fig. 8 in the modification C⁴ the structure is similar to that of Fig. 5, except that one strong screw 30' located near the root of the bolt shank B is substituted for the two screws 15 and 16. Nevertheless the lateral 70 projections 1 and 2 strengthen the shank against a tendency to turn.

In Fig. 9 the structure C⁵ is similar to that of Fig. 6, except that the web portion A assumes a substantially elliptical formation, 75 the toe 4 being illustrated. It is to be understood, of course, that the toe 4 may be eliminated in this modification also by providing means for attaching the same through to the rear frame 24.

80 What is claimed and what is desired to be secured by United States Letters Patent is:—

1. An article of manufacture comprising a window frame adapted to be built into 85 masonry building construction having a pair of safety-window-cleaning-device-anchors fixed thereto at predetermined locations, each said anchorage having a thin web portion secured to the outer wall of said 90 window frame and a bolt head fixed to said web-portion and extending out from said window frame at a locality not adapted to be covered with masonry.

2. In an anchor bolt for safety window 95 cleaning devices, a flat elongated web portion having a lateral projection near its outer end and adapted to be secured flat against the outer face of a window frame; and a headed bolt shank formed at the outer 100 end of said web portion and extending out therefrom at an obtuse angle to the plane of said web portion.

3. An anchorage for safety window cleaning devices comprising a web portion having 105 one or more rearwardly extending members and at the front one or more members extending generally transversely to said rearwardly extending member, said members having perforations to accommodate screws; 110 and a shank having a bolt head extending out obliquely from said one or more laterally extending members of said web portion.

115 In witness whereof, I have signed my name to this specification, in the presence of two subscribing witnesses.

JOHN K. GREEN.
